US0D1053860S

(12) **United States Design Patent** (10) **Patent No.:** **US D1,053,860 S**
(45) **Date of Patent:** ** *Dec. 10, 2024

(54) **HOLDER FOR ELECTRONIC DEVICES**

(71) Applicant: **SHENZHEN LISEN INTELLIGENT CO., LTD.**, Shenzhen (CN)

(72) Inventor: **Rufeng Yang**, Shenzhen (CN)

(73) Assignee: **SHENZHEN LISEN INTELLIGENT CO., LTD.**, Shenzhen (CN)

(*) Notice: This patent is subject to a terminal disclaimer.

(**) Term: **15 Years**

(21) Appl. No.: **29/884,959**

(22) Filed: **Feb. 17, 2023**

CLAIM

The ornamental design for a holder for electronic devices as shown and described.

DESCRIPTION

FIG. 1 is a perspective view of a holder for electronic devices showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
